CONTROL DEVICE FOR DISPENSING NOZZLES

Donald E. Hawkins, Concord, Ronald S. Hawkins, Turlock, and Fred R. Hawkins, Waterford, Calif.

Application February 8, 1957, Serial No. 639,158

8 Claims. (Cl. 222—29)

This invention relates to, and it is a major object to provide, a novel device to control a liquid dispensing nozzle such as used for retail gasoline delivery at a service station; i. e., a device which is operative to hold a normally hand-operated nozzle open for a certain period of time, and to then cause the nozzle to shut off or close.

When the motor driven pump which feeds the liquid to the nozzle is of constant delivery type (as is a gasoline pump) the gallons per minute of delivery are known, or easily ascertained, and therefore—by simple calculation—the present device can be readily set to hold the nozzle open for the time required to dispense approximately a desired quantity of the liquid.

An additional object of the invention is to provide a control device, of the type described, which is especially designed—but not limited—for use in connection with a gasoline dispensing nozzle to which liquid is fed from a conventional constant-delivery, gallonage metering, and price calculating, type of pump. In particular, the purpose of the instant device is primarily as an operator's aid in that it permits the nozzle—after engagement in the gasoline tank throat of a motor vehicle—to be latched open, and to thereafter automatically release the nozzle so that it closes after approximately the requested gallonage, but with some under-feed, has been dispensed. Thus, while the nozzle is held open the operator is free to attend to other service requirements on the vehicle, and after the nozzle automatically closes, such operator merely completes the sale by hand-feeding the remainder of the order, while watching the precision meter of the pump.

It is also an object of the invention to provide a control device, for dispensing nozzles, which is designed for ease and economy of manufacture and installation, and convenience of use.

Still another object of the invention is to provide a practical and reliable control device for dispensing nozzles, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of a gasoline dispensing nozzle fitted with the device of the present invention; the device being in its released position.

Fig. 2 is an enlarged transverse sectional elevation taken through the nozzle and showing the device from the rear; such device being in an operative position and just before occurrence of the automatic release of the nozzle hand lever.

Fig. 3 is a similar view, but with the device mainly in section.

Fig. 4 is a side elevation, in section, taken on line 4—4 of Fig. 2.

Referring now more particularly to the drawings, and to the characters of reference marked thereon, the invention is here shown as mounted in connection with

2

a gasoline dispensing nozzle, indicated generally at 1, which includes a tubular body 2 connected at the front with a delivery spout 3; such tubular body 2 being connected at the rear to the hose 4 which leads from a constant-delivery type gasoline pump (not shown).

5 A hand lever 5 is disposed beneath the body 2, and said lever is pivoted at the forward end, as at 6, to the lower end of a link 7 which extends from the automatic full tank shut-off mechanism enclosed within the housing, as at 8.

Intermediate its ends the hand lever 5 is adapted to work the upwardly movable plunger 9 of the nozzle control valve, which is enclosed within an intermediate portion of the body 2 and not here shown.

15 For the purpose of this invention it suffices to state that when the hand lever 5 is raised, the plunger 9 is pushed upwardly, which opens the nozzle 1; the latter closing automatically when said lever 5 is hand-released. Also, even though the hand lever 5 may be in a raised nozzle opening position, the plunger 9 is permitted to lower when the full tank shut-off mechanism of the nozzle functions, and at which time the link 7 shifts downwardly a distance sufficient for the plunger 9 to lower to a nozzle closing position.

20 25 The hand lever 5 is encompassed by a dependent, somewhat U-shaped guard 10 attached at its upper end portion to a boss 11 formed with the body 2.

The foregoing is generally conventional, and to such a nozzle—or an equivalent type—we attach our invention, and which is generally comprised of a releasable latch mechanism, indicated generally at 12. Such releasable latch mechanism 12—which is controlled by a timer—serves the purpose of holding the hand lever 5 in a nozzle opening position, while an approximate—but with some under-feed—gallonage is fed by the nozzle through the delivery spout 3.

30 35 More specifically, said releasable latch mechanism 12, which is shown in its released or out-of-operation position in Fig. 1, comprises—as reflected in detail in the remaining views of the drawings—the following:

40 A fixed or non-rotary transverse spindle 13 extends through the boss 11 and projects at the ends beyond opposite sides thereof; the projecting ends of the spindle 13 extending through the adjacent ends of the rear leg 45 of the hand lever guard 10, and outwardly thereof providing the primary journal for the upper ends of transversely spaced parallel swing arms 14 which—when the mechanism 12 is in released position—extend at a downward and rearward incline.

45 Beginning intermediate their ends the swing arms 14 converge in a rearward and downward direction to integral connection with a rigid link 15 which includes dependent ears 16.

50 55 A relatively short lever 17 is pivoted intermediate its ends, as at 18, between the ears 16, projecting in opposite directions therefrom. The link 15, at its upper end, is formed—on the back side—with ears 19; a two-part toggle linkage 20 being connected between the ears 19 and the corresponding end of the lever 17 by means of pivots, indicated at 21 and 22. The toggle linkage 20 includes, at its center pivot, a torque spring 23 which tends to hold said linkage 20 straightened out, and at which time the linkage is parallel to the rigid link 15.

60 65 The link of the toggle linkage 20 which corresponds to the ears 19 is outer-end slotted, as at 24, and such slot receives—on the pivot 21—an ear 25 which is integral with a dog leg or inverted L-shaped control lever 26 which extends upwardly at a lateral incline or diagonal (see Fig. 2).

70 At its free end the control lever 26 is fitted with a roller 27 which rides on a rotary cam 28 formed by the periphery of a hub 29 included in a wind-up or

spring-clock type timer unit, indicated generally at 30, which unit is disposed to one side of the boss 11 coaxially of the transverse spindle 13.

The hub 29, which rotates in response to a setting of the timer unit 30, as will hereinafter appear, finds its primary journal on the adjacent projecting end portion of said spindle 13.

The general construction and operation of the timer unit 30 will hereinafter appear.

The edge configuration of the ear 25 at the point of engagement with the adjacent link of the toggle linkage 20 is such that when the control lever 26 is in substantially straight-line or parallel relation to the toggle linkage 20, it prevents such linkage from buckling from the full line to the dotted line position shown in Fig. 4. However, upon control lever 26 swinging forwardly to its dotted line position in Fig. 4, and which occurs during operation of the device, as will hereinafter appear, the linkage 20 is caused to buckle outwardly or rearwardly to its dotted line position in said figure. The control lever 26 is urged by a tension spring 31 in a direction such that the roller 27 maintains contact with the rotary cam 28.

The lever 17, at the end portion opposite the pivot 22, has a headed bolt 32 threaded therethrough; the bolt head being indicated at 33, and which head is uppermost when said lever 17 is substantially horizontal. With the lever 17 in said substantially horizontal position, the bolt head 33 is disposed so that it will engage beneath the rear end of the hand lever 5 when the latter is pulled upwardly to a nozzle opening position, and as shown in full lines in Fig. 4.

The timer unit 30 includes, with—and projecting outwardly from—the hub 29, an enlarged rotary winding case 34 whose outer portion is peripherally knurled, as at 35, for the purpose of non-slipping finger engagement.

Axially inwardly of the knurled portion 35 the case 34 is fitted—externally—with the side by side scale bands or rings, indicated at 36 and 37, and which rings are rotatably adjustably secured to said case. The ring 36 is scaled, as at 38, in terms of gallonage, and a pointer 39 fixed relative to the spindle 13 spans both rings and reads on said scale 38 as well as on a scale 40 on ring 37; the scale 40 being in terms of price per gallon. Another pointer 41—parallel to pointer 39—likewise spans and reads on both scales; the pointer 41 being fixed to a snap ring 42 which is frictionally but turnably engaged in a channel 43 in case 34 outwardly of ring 37.

At the end of the spindle 13 which projects through the hub 29 and into the rotary winding case 34, said spindle includes an enlarged radial end plate 44 to which is secured a stationary back plate 45 of a wind-up or spring-clock type mechanism, indicated only in part at 46. The arrangement is such that with manual winding in one direction of the rotary case 34 to a certain extent, but less than 360 degrees, said mechanism 46 will then slowly return or rotate the case 34 in the opposite direction.

A torque spring 47 about the spindle 13 at the end opposite the timer unit 30 cooperates with the adjacent swing arm 14 in a manner to normally urge both of said arms to a rearwardly swung and downwardly inclined position with the releasable latch mechanism 12 in an out-of-the-way position, as shown in Fig. 1. The swing arm 14 opposite the one which is engaged by the torque spring 47 is fixed at its inner end with a sleeve 48 which surrounds the spindle 13 and occupies a position between the latter and the hub 29.

At its outer or free end, and within the rotary case 34, the sleeve 48 is formed with a radial finger 49 which normally lies in the path of rotation of a crank 50 on the end of a rotary shaft 51 included in the timing mechanism 46; such mechanism being permitted to operate only when the shaft 51 can freely rotate. Hence, when the swing arms 14 are in their rearwardly swung position

with the releasable latch mechanism 12 out of play, as in Fig. 1, the finger 49 prevents the crank 50 and the rotary shaft 51 from turning. However, when the swing arms 14 are swung forwardly, for use of the latch mechanism 12 in the manner which will hereinafter appear, the radial finger 49 is moved to an out-of-the-way position so that said crank 50 and rotary shaft 51 may rotate without interference.

In use of the above described control device the operator—after receiving the order from the customer—manually turns the rotary case 34 clockwise until the pointer 39 reads on scale 38 at the desired gallonage, or on scale 40 at the desired price; the pointer 41 then preferably being engaged in side by side relation with said pointer 39 and reading substantially on the same gallonage or price setting. With such turning of case 34, and setting of the pointers, the timer unit 30 does not immediately begin to run, as the crank 50 remains in engagement with the radial finger 49.

Thereafter, with the delivery spout 3 disposed in the neck of the vehicle's gasoline tank, the operator raises the hand lever 5 and immediately swings the releasable latch mechanism 12 downwardly to a substantially perpendicular position. With straightening out of the toggle linkage 20, the lever 17 assumes a substantially horizontal position and the bolt head 33 engages under the rear end of the raised hand lever 5. At the same time the control lever 26—being disposed in substantially straight-line relation to the toggle linkage 20, as in Fig. 4—holds the entire latch mechanism 12 in its operative position; this for the reason that the roller 27 is riding on the rotary cam 28.

With the latch mechanism 12 thus set in its operative position the hand lever 5 is held raised, with the nozzle 1 open and delivering through the spout 3.

When the latch mechanism 12 is swung to its substantially perpendicular operative position, as above described, the radial finger 49 clears the crank 50 so that the timer unit 30 begins to function, and which includes rotation of the case 34 in a counter-clockwise direction.

After the case 34 has rotated, under the influence of the timing mechanism 46 to the extent predetermined by the setting of pointer 39 on scale 38 or scale 40 (the pointer 41 having remained at the original gallonage or price setting as a "memory" marker for the operator), the roller 27 of control lever 26 falls into a notch 52 formed in the periphery of said cam 28. When this occurs, the control lever 26 swings forwardly from its full-line to its dotted-line position, and the toggle linkage 20 is caused to buckle rearwardly from its full-line to its dotted-line position, all as shown in Fig. 4. Upon such occurrence the lever 17 is tilted so that its forward end drops down (also shown in dotted lines in Fig. 4), and this permits the entire latch mechanism 12 to snap rearwardly to its clearance or out-of-the-way position, as shown in Fig. 1; the hand lever 5 then having been returned to its fully lowered nozzle closing position.

After the latch mechanism 12 thus releases, the operator manually grasps the nozzle and uses the hand lever 5 to open the nozzle so as to feed any remaining gallonage to precisely complete the order, and which the operator accomplishes by visually observing the precision meter of the pump.

The device of the present invention can be readily adjusted so that it properly controls the nozzle 1 for delivery, with slight under-feed, from the nozzle 1; this being accomplished merely by adjustment of the bolt 32, which in turn varies the position of lever 5 and alters the flow through the nozzle 1 when the latch mechanism 12 is in use.

With the instant control device attached to a gasoline dispensing nozzle 1, such device—when in use—permits the operator to fuel and service a motor vehicle more efficiently and in less time than usual, and additionally makes more practical fuel dispensing noz-

zles, particularly those of automatic, full tank shut-off type.

With respect to this type of nozzle, it is to be noted that if the fuel tank becomes full before the timer unit 30 releases the latch mechanism 12, the link 7 of the full tank shut-off mechanism shifts downwardly so that the plunger 9 lowers and closes the nozzle; the latch mechanism 12 then also automatically releasing and swinging to its out-of-the-way position.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. In combination, on a dispensing nozzle including a body supporting a hand lever for movement between nozzle closing and opening position, a releasable mechanism operative to hold the hand lever in nozzle opening position, a hand-set timer mounted in connection with the body, the timer including a movable part, and means responsive to movement of such part arranged to cause release of said mechanism to permit return of the hand lever to nozzle closing position; the timer being of spring-clock type and including a rotary case manually wound in one direction to pre-set said timer and self-unwinding in the opposite direction, said movable part being a rotary cam in connection with the case.

2. In combination, on a dispensing nozzle including a body supporting a hand lever for movement between nozzle closing and opening position, a releasable mechanism operative to hold the hand lever in nozzle opening position, a hand-set timer mounted in connection with the body, the timer including a movable part, and means responsive to movement of such part arranged to cause release of said mechanism to permit return of the hand lever to nozzle closing position; the timer being of spring-clock type and including a rotary case manually wound in one direction to pre-set said timer and self-unwinding in the opposite direction, a peripheral scale on the case, and a pointer fixed relative to the body readable on said scale.

3. A combination, as in claim 2, including another peripheral scale on the case, and a separate pointer mounted on the case and readable on said other scale; said separate pointer being adjustable about the case circumferentially thereof.

4. In combination, on a dispensing nozzle including a body-supporting a hand lever for movement between nozzle closing and opening positions, the hand lever being below and extending lengthwise of the body, the hand lever having a rear end which is moved toward the body when said lever is in nozzle opening position, a transverse spindle mounted in connection with and projecting laterally of the body generally above said end of the hand lever, a swing arm assembly pivoted on the spindle for swinging movement in a longitudinal vertical plane below the body, yieldable means tending to swing the arm

assembly rearwardly and upwardly to an initial position clear of the lever, a latch mechanism mounted on the free end portion of the arm assembly, said latch assembly being adapted to engage beneath said rear end and releasably hold the hand lever in nozzle opening position when the arm assembly is swung forwardly and downwardly from said initial position, and a time-responsive control device associated with and arranged to cause the latch mechanism to release from said end of the hand lever to permit the latter to return to nozzle closing position and the arm assembly to swing back to said initial position.

5. A combination, as in claim 4, in which said mechanism includes a toggle linkage adapted to be broken in a given direction to cause such release, the control device including a rotary cam, and a linkage breaking lever extending therefrom and riding the cam.

6. A combination, as in claim 4, in which the latch mechanism includes a rigid link which upstands adjacent said end of the lever when the arm assembly is swung forwardly and downwardly from said initial position, a longitudinal lever transversely pivoted intermediate its ends on the lower portion of the fixed link, a head projecting from said longitudinal lever adjacent its forward end and adapted to engage under said end of the hand lever, an ear projecting rearwardly from the rigid link above the rear end of the longitudinal lever, and a toggle linkage pivotally connected between said rear end of the longitudinal lever and said ear, said linkage being held straight and parallel to the rigid link when such seat is engaged under said end of the lever; the time-responsive control device including a rotary cam turnable about the spindle as an axis, and a toggle linkage breaking lever extending therefrom and riding the cam, the toggle linkage when broken causing the longitudinal lever to raise at the rear and lower at the front so that the hand lever is returned to nozzle closing position and the arm assembly is released to swing back to said initial position.

7. A device, as in claim 6, in which said head is mounted on the longitudinal lever for adjustment toward and from the same in the direction of the hand lever.

8. In combination on a dispensing nozzle which includes a body supporting a hand lever for movement between nozzle closing and opening positions, a releasable latch mechanism operative to hold the hand lever in nozzle opening position, and a time-responsive control device associated with and arranged to cause release of said mechanism to permit return of the hand lever to nozzle closing position; a transverse spindle mounted in and projecting at both ends from the body, means mounting the latch mechanism on a projecting portion of the spindle, and means separately supporting the control device from one end of the spindle.
